UNITED STATES PATENT OFFICE.

BENJAMIN SCHNITZER, OF AKRON, OHIO, ASSIGNOR TO GOODYEAR-ZEPPELIN CORPORATION, OF AKRON, OHIO, A CORPORATION OF DELAWARE.

AIRSHIP.

Application filed July 17, 1925. Serial No. 44,239.

My invention relates to airships and it has particular relation to a form and arrangement of gas containers adapted to be utilized in dirigible airships for the purpose of facilitating safe navigation thereof.

One object of my invention is to provide an airship having gas containers therein which are so constructed and arranged that both non-inflammable gas and inflammable gas may be utilized for lifting purposes without danger of accidental explosion of the inflammable or combustible gas.

Another object of my invention is to provide an airship in which a fuel gas having less lifting power than the lifting gas, is adapted to be utilized, and which is protected from accidental explosion by completely surrounding the combustible gas with non-inflammable gas.

In the development of navigable airships in which gas is employed as a lifting medium, many inventions have been conceived, with a view to reducing the hazards incident to utilization of combustible or inflammable gases. Airships have heretofore been constructed in which containers for a relatively light explosive or combustible gas, such as hydrogen, have been disposed centrally within compartments having gas cells therein inflated with a relatively heavier non-inflammable gas, such as helium or nitrogen. This was done in order to isolate the combustible gas and prevent dangerous mixtures which are liable to occur when air and hydrogen are exposed to each other. It has been a difficult matter to properly secure combustible gas containers for the relatively light inflammable gas within the non-inflammable gas cells without subjecting the latter to liability of being damaged during changes in conformation of the cells incident to the variation in gas pressure caused by changes in temperature.

By my invention I propose to obviate the above enumerated disadvantages by employing supplemental gas bags inflated with relatively heavy fuel gas or gas not lighter than the lifting gas. These gas bags are suspended wholly within one or more of the main lifting gas cells. I prefer to utilize helium as the main lifting gas. The use of a relatively heavy fuel gas renders it possible to employ simple and efficient suspension for the containers of such gas. Penetration of the main

containers or cells by the suspension lines 55 or cords is avoided by the use of relatively heavy gas. This arrangement permits the inner or fuel gas bags to move freely within the lifting gas container about its suspension point without exerting any objectionable strain on any of the gas containers.

In order to prevent loss of helium, which is relatively scarce and expensive, the main gas cells are inflated with this gas only to approximately 80 to 85 per cent of their 65 capacity. Such limited inflation permits the helium to expand or contract under conditions of various changes in temperature and pressure incident to the ascent and descent of the airship. The remaining 15 to 70 20 per cent of the capacity of the main helium cells is occupied by the relatively small fuel gas bags or containers. The fuel gas fed to the motor is consumed in the same proportion with respect to weight as the consumed gasoline.

For a better understanding of my invention, reference may now be had to the accompanying drawings forming a part of this specification, of which:

Fig. 1 is a longitudinal sectional view of an airship illustrating, diagrammatically, the features of my invention;

Fig. 2 is a cross-sectional view illustrating, diagrammatically, an airship embodying my 85 invention, the view being taken substantially along the line II—II of Fig. 1; and

Fig. 3 is a view on a larger scale showing in detail one of the suspension elements employed in my invention.

In practicing my invention I provide a plurality of adjacently disposed gas cells or containers 10, which are adapted to be inflated with a non-inflammable lifting gas, such as helium, and which are disposed within a hull or envelope 11 of an airship. The cells or main containers 10 are suspended from the hull or envelope 11 at their uppermost points, as indicated at 12. The lower portion of each gas cell 10 is unattached, as 100 illustrated at 13, in order that the cell may partially collapse when the gas therein contracts.

A fuel gas container 14 is disposed wholly within each gas cell 10 and is suspended 105 from the top thereof by means of a series of cables or cords 15 secured along a row of connecting elements 16. It is to be under-

stood that the gas container 14 may be omitted from one or more of the cells 10 if desirable. Since the fuel gas contained in the bag 14 is heavier or not lighter than the helium surrounding it, stabilizing lines or cords, other than those shown at 15 are not necessary. Each of the connecting elements 16, as best illustrated in Fig. 3, consists of reinforcing patches 17 and 18 secured firmly about a ring 19, one-half of which extends above and the other half of which extends below the wall of the gas cell 10. The lower portion of the ring 19, on the inner side of the gas cell, serves as an anchor for the suspension cords 15, while the upper half of the ring serves as an anchor for lashing the ring 19 to the hull or envelope of the airship at the points 12, by means of cords 20, or other suitable connecting means.

Suitable conduits 22 are connected to the fuel gas bags 14 and serve the purpose of feeding the gas to the motors (not shown). The container 14 may be filled with gas by means of the conduits 22, or if desired, an additional filling conduit may be provided. As an additional safe guard against accidental explosion of the fuel gas, a relatively large conduit 23 incloses each of the hose conduits 22 and is adapted to contain non-combustible gas or liquid, which completely isolates each hose conduit 22. If desirable, this protective inclosing conduit may be formed with a separate gas containing compartment, or it may be in direct communication with the interior of the gas cell 10. The conduits 22, which are preferably composed of rubber hose, are connected between the cell 14 and the wall 11 with a certain degree of slackness therein to permit freedom of movement of the gas bag 14 within the cell 10. As the maximum roll or list of the ship never exceeds 10°, the length of the hose 22 need exceed the normal distance between the cell 14 and the wall 11 by but very little. It will be apparent that, by the use of a fuel gas heavier than the non-inflammable gas, I have secured several advantages over the previously known and used combination of gases. One advantage is that the container may be suspended by any ordinary means from the top of the envelope framework without the use of the additional stays necessary when a gas lighter than the non-inflammable gas is used. Another advantage is that the heavier gas is forced downwardly through the conduits 22 to the motors by the lighter non-inflammable gas without the use of any pumping operation.

From the foregoing description, it will be apparent that the lifting gas containers and fuel gas containers constructed according to the principles of my invention render it possible to navigate dirigible airships with maximum safety and, at the same time, it is possible to conserve practically all of the relatively expensive lifting gas by utilizing

fuel gas instead of gasoline to operate the motor of the airship.

Although I have illustrated but one form which my invention may assume and have described in detail but a single application thereof, it will be apparent to those skilled in the art that it is not so limited but that various minor modifications and changes may be made therein without departing from the spirit of my invention or from the scope of the appended claims.

What I claim is:

1. The combination with an airship comprising a hull portion having an inflatable gas cell therein and a gas bag disposed within the hull portion cooperating with the gas cell to occupy the space within the hull portion, of a lifting gas for inflating the gas cell, and a combustible gas heavier than the lifting gas for inflating the gas bag. 85

2. An airship comprising a hull, a lifting gas cell provided with means projecting from the inner and outer surfaces thereof, suspension members for connecting said means to the hull and means positioned upon the upper 90 inner portion of the cell connected to the first named means for suspending a gas bag wholly within the cell.

3. An airship comprising a hull, a lifting gas cell provided with a row of elements for 95 connecting the cell to the hull adjacent the top thereof, and means positioned at intervals longitudinally of the hull upon the upper inner portion of the cell cooperating with the elements for suspending a gas bag 100 wholly within the cell.

4. A gas bag comprising a cell adapted to be inflated with non-inflammable lifting gas, a gas bag provided with suspension means disposed wholly within the cell, a motor supply conduit leading from the gas bag through the wall of the cell and means for isolating the supply conduit with said non-inflammable gas beyond the wall of the cell. 105

5. An airship comprising a plurality of 110 cells adapted to be inflated with non-inflammable gas, a gas bag provided with suspension means disposed wholly within each cell, a motor supply conduit leading from the gas bag through the wall of the cell and a second 115 conduit inflated with non-inflammable gas inclosing the supply conduit beyond the wall of each cell.

6. An airship comprising an outer protective framework, a gas cell disposed within said framework and suspended therefrom at the uppermost portion only, and a gas bag disposed wholly within said first named cell and spaced from the walls thereof, said gas bag being suspended from said framework 125 at the uppermost portion only.

In witness whereof, I have hereunto signed my name.

BENJAMIN SCHNITZER.
